W. N. BEAT

GOLF CLUB

Filed Feb. 21, 1925

BY

INVENTOR.
William N. Beat.
Richard L. Brown
ATTORNEY.

UNITED STATES PATENT OFFICE.

WILLIAM NEISH BEAT, OF BROOKLYN, NEW YORK.

GOLF CLUB.

Application filed February 21, 1925. Serial No. 10,903.

To all whom it may concern:

Be it known that I, WILLIAM N. BEAT, a subject of the King of England, residing at Brooklyn, in the county of Kings and State 5 of New York, have invented certain new and useful Improvements in Golf Clubs, of which the following is a specification.

This invention relates to golf clubs and more particularly to a novel and improved bottom plate whereby a properly balanced club head may be produced and the weight distributed so as to assist in overcoming certain defects in the playing of the individual.

It is well known among professional and amateur golfers that the balance of the golf club head is of primary importance in the perfection of the golf swing and that both right hand and left hand golfers have the tendency to cut across the face of the golf ball at the moment of impact to produce either a slice or a hook. In order to overcome these defects, instead of altering the swing, it has been the practice of modifying the golf club head by shifting the weight 20 either toward the heel or the toe of the club but the objection to this practice has been, for the most part, that it produced an unevenly balanced head.

One of the objects, therefore, of my invention is to produce a properly weighted and balanced club head by means of a special type of plate including means for varying the balance of the plate so that when positioned in the club head, the balance of the head will be maintained whereby the tendency to slice or hook the ball by reason of the improper swing, may be overcome.

In order to more fully understand and appreciate my invention reference is had 40 to the accompanying detailed drawings wherein,

Figure 1 is a view showing the face of the golf head, embodying my invention.

Figure 2 is a rear view of the head.

Figure 3 is a bottom view showing the head and plate.

Figure 4 is a bottom view, partly in section.

Figure 5 is a similar view to Figure 4 showing the weight distributed within the head and carried by the plate.

Figure 6 is a perspective view of the head, the plate being removed.

Figure 7 is a perspective view of the plate, 55 detached from the head.

Figure 8 is a cross sectional view through the head and plate when assembled.

Figure 9 is a bottom plan of the plate shown in Figure 7.

Figure 10 is a modified form of a portion 60 of the plate showing the use of two kinds of metal in its construction.

Figure 11 is a vertical, sectional view through the modified form of plate shown by Figure 10.

Referring now to the drawings wherein like reference characters designate corresponding parts throughout the several views, 5 designates the shaft, 6 the heel, 7 the toe and 8 the driving face of the conventional 70 type of club head, such as a brassie or brassie-driver. The bottom face 10 of the club head is partially cut away as indicated at 11 from the front to the rear so as to receive the countersunk plate, designated in its entirety by numeral 12. The plate 12 is curved slightly to conform to the bottom curvature of the face 10, the front edge 13 of said plate extending to the edge and flush with the driving plate of the club head. 75 Entering the body of the club head from the rear face 14 thereof and in line with the cut away portion 11, are a plurality of spaced openings 15, which are located centrally of the body portion of the head, there being 85 shown in the preferred embodiment of my invention, three of such openings as illustrated clearly by Figure 6 of the drawings. The plate 12 being provided with an enlarged head 16, which is adapted to fit flush 90 with the rear face 14, being slightly curved to conform to the curvature of the club head. Formed integral with the enlarged back head 16, I have provided three tubular or cylindrical weight receiving plugs 17, which 95 are preferably threaded on their interior surface as indicated by numeral 18 and adapted to receive a metal filling 19, such as molten lead, for instance, which may be introduced into the respective tubular plugs, 100 so that the weight may be shifted or varied toward the heel or the toe of the plug. In the form of the invention shown by Figures 4 and 5 and the plates illustrated, the plugs decrease in length toward the heel of the 105 plug, but if so desired, either end plug 18^a or 18^b may be partially cut away or filled with molten lead or any filling, so the weight may be shifted or varied on either side of the central plug. In some instances, it may 110

- only be necessary to fill the central plug partly or entirely or to partially cut away either of the end plugs 18^a or 18^b as the particular individual may desire. Consequently, it will be recognized that where it is desired that weight of the club head be modified so that the individual desires to correct the defect in the golf swing, which produces either a slice or a hook upon striking the golf ball, such a correction may be made by varying or shifting the weight, as above indicated.
- As is the practice in attaching plates to golf heads, suitable screws 20 are provided, which pass through the plate into the body of the club head proper. By simply removing the screws, the plate and its plug may be removed as a unit and the change or modification or location in the weights distributed as above described.
- In Figures 10 and 11, I have shown a plate formed of two different kinds of material, such as aluminum and brass, in which instance, the brass head 16^a is provided with a tongue 17^a whereby it may interfit in a slot or groove in an aluminum plate 18^a. Since the aluminum is comparatively light, the brass head portion 16^a will tend to balance the club head and throw the weight toward the rear face 14, when positioned in the club head in the manner above indicated. Of course in this form of the invention, the tubular members 17 are also formed with the brass head 16^a for the purposes above set forth.
- While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.
- Having thus described my invention, what I claim as new and desire to secure by United States Patent is:—
1. In a golf club, the combination of a head having a shallow groove in its bottom face and a plurality of apertures extending inwardly from the rear face of the head and a weighted plate countersunk in said groove and said apertures.
  2. In a golf club, the combination of a head having a shallow groove in its bottom face extending from the front face to the rear face thereof, said rear face having a plurality of apertures directed inwardly toward the center of the head and a weighted plate countersunk in said groove and said apertures.
  3. In a golf club, the combination of a head having a shallow groove in its bottom face and a plurality of contiguous apertures directed inwardly from the rear face thereof toward the center of the head and a plate countersunk in said groove, said plate having weighted means adapted to enter the said apertures.
  4. In a golf club, the combination of a head having a shallow groove in its bottom face and a plurality of contiguous apertures directed inwardly from the rear face thereof toward the center of the head, a plate countersunk in said groove, said plate having a weighted head adapted to lie flush with the rear face of the head and weighted members extending within the said apertures.
  5. A sole plate for golf clubs having a thickened end portion and weighted means extending inwardly over the top face of said plate.
  6. A sole plate for golf clubs having a weighted, thickened end portion formed therewith and weighted means integral with the said end portion extending inwardly over the top face of said plate.
  7. A sole plate for golf clubs having a weighted, thickened end portion and weight receiving extensions formed with the said end portion, said extensions being directed inwardly over the top face of said plate.
  8. A sole plate for golf clubs having a weighted, thickened end portion and tubular, weight receiving extensions formed therewith, said extensions being spaced relative to each other and directed inwardly toward the center and over the top face of the plate.
  9. A sole plate for golf clubs having a weighted, thickened end portion, spaced tubular members formed with the said end portion and directed inwardly toward the center and over the top face of the plate, said members being internally threaded for confining a weighted substance.
  10. A sole plate for golf clubs having a weighted, thickened end portion, a plurality of spaced tubular members formed with said end portion and directed inwardly toward the center and over the top face of the plate, said members being of unequal length and internally threaded for confining a weighted substance introduced therein.
- In testimony whereof I affix my signature.
- WILLIAM NEISH BEAT.
